UNITED STATES PATENT OFFICE

JEANNETTE FRENCH, OF NEW YORK, N. Y., ASSIGNOR TO UNIQUE MANUFACTURING COMPANY, INC., OF NEW YORK, N. Y., A CORPORATION OF DELAWARE

SWEEPER

Application filed October 20, 1931. Serial No. 569,866.

This invention relates to surface treating means and my improvements are directed to a hand-propelled device which may be provided with two separate and distinct cleaning implements, which may be brushes having different characteristics, one being a relatively stiff brush for sweeping carpets, and the like, and the other a soft brush for sweeping hard surfaces; or the treating implements 5 may be of suitable character for polishing, dressing, or otherwise treating floors or similar surfaces.

In cleaning or otherwise treating carpets, floors and similar surfaces, it is often desirable to employ different cleaning or treating devices on surfaces of different character, or to employ different cleaning devices successively on the same surface. Thus for sweeping carpets or rugs it may be desirable 15 to employ a fairly stiff brush, whereas for sweeping waxed floors or other surfaces which are apt to be marred by the bristles of a stiff brush it is desirable to employ a relatively soft brush. The principal object of 20 my invention is to provide an improved means embodying a plurality of such sweeping or cleaning devices, each of which may be rendered operative at will while the remaining device or devices are inoperative.

In the embodiment of my invention herein illustrated I disclose a sweeper having two rotary brushes one of which may be a soft brush and one a stiff brush. The sweeper is provided with traction members which may 25 be wheels of the usual type, and means are provided whereby either one of the brushes may be connected with the wheels so as to be operated thereby and at the same time the other brush is disconnected from the wheels 30 and raised from the surface so as to remain idle while the sweeper is moving thereover. The sweeper is provided with the usual long handle to move it over the floor, and as is the practice with this type of sweeper the 35 handle is pivoted to the sweeper body so

that, in its operative positions, it may extend from one end or the other of the sweeper body. For the purpose of rendering either brush operative, at will, I mount the brushes in such a manner that when the handle is 50 swung from one end of the sweeper body to the other, one of the brushes is moved downwardly into contact with the floor, and being in engagement with the traction wheels is in a position to be operated thereby when the 55 sweeper is moved over the floor. This same movement of the handle lifts the other brush away from contact with the floor.

The brushes are preferably mounted on parallel axes, in spaced relation with a dust 60 pan between them, and in the preferred construction the arrangement is such that the operative brush is always the forward brush of the sweeper.

My improved sweeper structure includes a 65 casing within which two pairs of traction wheels are journaled, while the respective brushes are disposed within the casing near opposite ends thereof, and respectively beyond the pairs of traction wheels, said 70 brushes carrying circular frictional disks that are adapted to be rotated from the traction wheels with which they are associated.

The sweeper handle has a bail which is 75 journaled by pivotal portions thereof in opposite sides of the casing, said pivotal portions carrying disks with which are connected links that themselves are pivoted to bars which each have a bearing for a brush and are slotted to receive the axles of the 80 traction wheels.

Since the disks are secured to the bail pivotal portions the swinging movement of the handle in one direction causes the bars, which use the traction wheel axles as fulcrum, 85 to raise the brush at one end of the casing out of contact with the floor surface and to depress the brush at the other end of the casing into operative contact with said surface.

A feature of the invention is the ease and 90

simplicity with which the cleaning brushes can be removed from the casing and replaced therein without disturbing the mechanism, this provision for interchangeability enabling the most suitable brushes for any given purpose to be selected, and also facilitating frequent cleaning of the brushes, and their renewal when worn.

A further feature of the invention resides in the provision of a dust, etc., receiving box, said box being entered within the casing for service, from the upper surface thereof, the casing having an opening in its top for that purpose. Said box, which has a central partition, is adapted to lie between the brushes and has end openings adjacent the brushes to receive dirt, etc., swept up thereby.

Other features and advantages of my invention will hereinafter appear.

In the drawings:

Figure 1 is a horizontal sectional view of my improved surface treating device taken on the line 1—1 of Fig. 2.

Fig. 2 is a side sectional view taken on the line 2—2 of Fig. 1.

Fig. 3 is a sectional view taken on the line 3—3 of Fig. 1.

Fig. 4 is a side sectional view taken on the line 4—4 of Fig. 1, and

Fig. 5 is an endwise section taken on the line 5—5 of Fig. 4.

In said views let 1 indicate a casing adapted to contain the cleaner mechanism and having pairs of traction wheels 2, 3, which are respectively journalled in bearings 4 provided therefor in said casing, said wheels having the axles 5.

The outer cylindrical faces of the wheels are lined with friction material such as rubber, forming the usual traction tires for the wheels. 6 indicates a handle for the sweeper, which handle is provided at its lower end with a bail or yoke-shaped member 6a pivoted in the side walls of the sweeper casing 1 as shown at 7, and 8 represents the portions of the bail which project inside the casing. Each portion 8 has a collar 9 mounted upon it and secured thereto as by means of a set-screw 10. U-shaped links 11, 12 are pivotally mounted at their upper ends on each disk 13, and said disks are mounted respectively on the projecting portions 8 of the bail and fixed to collars 9. The lower ends of links 11, 12 are pivotally mounted at the inner ends of lever members 14, 15. These lever members have slots 16, 17 by means of which they are mounted upon the axles 5, of the traction wheels 2, 3, and are capable of rocking thereon. The outer ends of the lever members carry bearings in which sweeping brushes 24, 25 are rotatably mounted.

Each of these brushes is formed of a cylindrical core of any suitable material, carrying bristles. The bristles of one of the brushes, as for example brush 24, may be stiff and

adapted for cleaning carpets, rugs and rough surfaces generally, while the bristles of the other brush 25 may be soft and adapted for sweeping polished or waxed floors and smooth surfaces generally.

Projecting from the ends of the cores 24a, 25a of brushes 24, 25, are journals 26, which extend through and are rotatably mounted near the ends of lever members 14, 15, as shown at 27. The bearing 27 is cut away in order to enable the brushes to be removed and replaced easily. Friction wheels 28, 29, made of any suitable material, are secured to the outer ends of the journals 26. The ends 31, 32 of tension springs 30 are secured to the inner ends of lever members 14, 15, and the tension in the springs pulls the lever members inwardly and maintains contact under pressure between the brush friction wheels 28, 29, and the traction wheels 2, 3.

It will thus be seen that by pulling lever members 14 and 15 outwardly, the journals 26 are freed, thereby enabling the brushes to be removed easily from the casing. The extent of the outward movement of the members 14, 15 is limited to the requisite extent by the slots 16, 17 provided therein.

Associated with the brush friction wheels 28, 29, are cams 33, 34 shown fixed to the top of casing 1. In Fig. 2, brush 25 is in inoperative position and cam 34 holds friction wheel 29 out of contact with traction wheel 3.

The operation of my improved sweeper is as follows:

As the handle 6 is swung from one end of the body 1 to the other, disks 13 will be rotated. Referring to Figure 2, and supposing the handle 6 to be swung from right to left, turning disks 13 with it, then link 12 will be raised and link 11 lowered, thus lowering the inner end of lever member 14, rotating it about the traction wheel axle 5, pressing friction wheel 28 against cam 33, and pulling lever 14 outwardly along the slot 16. In this manner the brush 24 will be raised from the surface, and at the same time friction wheel 28 will be moved out of engagement with traction wheel 2, and the brush will therefore remain idle during the operation of the sweeper. Similarly, by the same movement of the handle from right to left, it will be seen that brush 25 will be moved into contact with the surface, and into operative engagement with the traction wheel 3. A reversal of the handle will cause the former brush to be moved into operative position and the latter brush into inoperative position.

A dust pan 35 which can be removed and replaced through the top of the sweeper casing 1, has lips 36 which rest on the top 37 of the casing 1, thereby supporting and holding the said dust pan in position. The dust pan has a bottom portion 38, the ends 39 of which are bent upwardly and inwardly so as

to lie near the brushes and direct the dirt into the pan in the sweeping operation. A partition 41 prevents dirt from the operating brush from being thrown against the idle brush. A handle 42 for the dust pan enables the latter to be removed readily from the sweeper-casing for emptying. A comb 43 is provided for removing hair and fluff-like material from the stiff brush 24. This comb is shown secured transversely in the dust pan in such position that its teeth engage with the bristles of the brush.

This application is a continuation in part of my application for sweeper, Serial No. 341,260, filed February 19, 1929.

Variations within the spirit and scope of my invention are equally comprehended by the foregoing disclosure.

I claim:

1. In a surface treating machine, in combination, a casing, traction members, treating devices having different characteristics, a pivotal handle, and means connecting said treating devices with said handle whereby the swinging of said handle in one direction or the other serves selectively to connect one or the other of said treating devices with said traction members for operation.

2. The combination with a surface treating machine having a casing and traction wheels, of two parallel, cylindrical treating devices, movable means mounted in said casing for carrying said devices, said devices having different characteristics, a pivotal handle, and means connecting said carrying means and handle, whereby the swinging of said handle in one direction or the other serves selectively and operatively to connect one or the other of said treating devices with said wheels for rotation of the devices.

3. In a surface treating machine, an elongated casing, two cylindrical treating devices mounted on parallel axes transversely of said casing, traction wheels mounted in the casing, a handle pivotally connected with said casing for operating said surface treating machine from either end thereof, and means controlled by the swinging movement of the handle toward either end of the machine for operatively connecting the treating device near the opposite end of the machine to a traction wheel.

4. In a surface treating machine, a casing, traction wheels mounted thereon, a handle having a bail journalled by pivotal portions in opposite sides of said casing, disks carried by said pivotal portions, links eccentrically pivoted to said disks, lever members having their inner ends pivoted to said links, each of said lever members, at a point intermediate its length, being pivotally and slidably mounted upon the casing, rotary treating devices journalled at the outer ends of said lever members, said treating devices including friction wheels, means to urge said

friction wheels into engagement with said traction wheels and fixed cams associated with each treating device which engage and move outward said associated treating device when the latter is raised, whereby the swinging of the handle in one direction or the other causes one treating device or the other to be placed in operative position while the other treating device is placed in inoperative position.

5. In a surface treating machine, a body casing, an elongated handle for moving said casing and operating said machine, said handle having a bail pivoted to said casing, lever members pivoted in said casing, treating devices journalled in said lever members, friction wheels carried by said treating devices, pairs of traction wheels mounted in opposite ends of said casing, and means of connection between said bail and said lever members, said handle when swung to one end of the casing moving one of said treating devices to bring its friction wheels into contact with the rims of an adjacent pair of traction wheels for rotation of the treating device thereby, and moving the other treating device to a position where it is inoperative, and said handle when swung in the opposite direction to the other end of the said casing, moving the first named treating device to a position where it is inoperative, and the second named treating device to a position for operation by engagement of its friction wheels with the rims of its adjacent pair of traction wheels.

6. In a surface treating machine, a casing, pairs of traction wheels mounted thereon, and floor treating devices, each floor treating device being capable of frictional operation by a pair of traction wheels, a handle having a bail that is journalled by pivotal portions thereof in opposite sides of the casing, disks carried by said pivotal portions, links eccentrically pivoted to said disks, lever members in pivotal engagement with said links, pairs of said lever members having bearings respectively for said treating devices and being slotted to receive the axles of the traction wheels, cams fixed in said casing respectively adjacent said treating devices to co-act therewith, and means whereby the swinging movement of said handle in one direction causes one of said treating devices to be moved by its associated links and levers against its adjacent cams, to be thus held out of contact with co-acting traction wheels, and the swinging movement of said handle in the opposite direction causes the other treating device to be similarly brought into contact with its adjacent cams and out of contact with its co-acting traction wheels.

7. In a surface treating machine, a casing, pairs of traction wheels mounted thereon, and floor treating devices, each floor treating device being capable of frictional operation

by a pair of traction wheels, a handle having a bail that is journalled by pivotal portions thereof in opposite sides of the casing, disks carried by said pivotal portions, links eccentrically pivoted to said disks, lever members in pivotal engagement with said links, pairs of said lever members having hook-shaped bearings at their outer ends respectively for said treating devices and being slotted intermediate their ends to receive the axles of the traction wheels, springs urging said lever members inwardly and thereby holding said treating devices in position, said lever members when pulled outwardly enabling said treating devices to be released and removed from the hook-shaped bearings, cams fixed in said casing respectively adjacent said treating devices to co-act therewith, and means whereby the swinging movement of said handle in one direction causes one of said treating devices to be moved by its associated links and levers against its adjacent cams, to be thus held out of contact with co-acting traction wheels, and the swinging movement of said handle in the opposite direction causes the other treating device to be similarly brought into contact with its adjacent cams and out of contact with its co-acting traction wheels.

8. In a sweeper, in combination, a casing having an opening in its upper portion, brushes supported in said casing, traction wheels journalled in said casing, actuating means between said traction wheels and brushes to rotate said brushes, a handle for operating said sweeper, a dust pan capable of being removably fitted within said casing, between said brushes, by way of said opening, and a partition for dividing said pan into two compartments for co-action, respectively, with said brushes.

9. In a surface treating machine, a casing, a brush rotatably supported by and inclosed within said casing and traction wheels journalled in said casing, said casing presenting an opening in its upper portion, one of the edges of said opening being spaced from the adjacent end wall of said casing to define a top portion overhanging said brush and a dust pan removably insertable within said opening.

10. In a surface treating machine, a casing, spaced brushes rotatably supported in said casing adjacent the end walls thereof, traction wheels journalled in and supporting said casing, said casing presenting an opening in its upper portion, opposite edges of said opening being spaced from adjacent end walls of said casing to define top portions overhanging the brushes, and a dust pan removably insertable within said opening to lie between said brushes.

11. In a surface treating machine, a casing, spaced brushes rotatably supported in said casing adjacent the end walls thereof, trac-

tion wheels journalled in and supporting said casing, said casing presenting an opening in its upper portion, opposite edges of said opening being spaced from adjacent end walls of said casing to define top portions overhanging the brushes, and a dust pan removably insertable within said opening to lie between said brushes, said dust pan comprising a top, a bottom, and side walls, and a partition connecting said top and bottom to define a dust-receiving compartment for each of said brushes.
